UNITED STATES PATENT OFFICE.

GEORGE C. WORTMAN, OF WORTMAN, COLORADO.

PUSH-CAR.

No. 905,121.

Specification of Letters Patent. Patented Nov. 24, 1908.

Application filed June 8, 1907. Serial No. 377,081.

To all whom it may concern:

Be it known that I, GEORGE C. WORTMAN, a citizen of the United States, residing at Wortman, in the county of Lake and State 5 of Colorado, have invented certain new and useful Improvements in Push-Cars; and I do declare the following to a full, clear, and exact description of the invention, such as will enable others skilled in the art to which 10 it appertains to make and use the same, reference being had to the accompanying drawings, and to the letters and figures of reference marked thereon, which form a part of this specification.

15 My invention relates to improvements in cars, my construction being more especially applicable to what are ordinarily known as push cars.

The object of the invention, is to provide 20 a construction of this class which may be tilted to a lateral position on either side of the car for either loading or dumping purposes.

By virtue of my improved construction, 25 the body of the car is movably mounted on a relatively stationary platform equipped with rollers, the central roller or a number of rollers in alignment being of considerable greater diameter than the rollers of the 30 outer edge of the car. The said body, however, is provided at its bottom with blocks which when the body of the car is in its normal position, engage the rollers of lesser diameter on the outer edge of the car and 35 thus cause the body of the car to occupy a horizontal position. When, however, the said body is slightly shifted laterally in either direction, its supporting blocks are disengaged from the rollers at the edge of 40 the car, the body will be automatically tilted or inclined to the dumping position and slide downwardly until certain devices with which its central portion is equipped, catch upon retaining pins mounted on the edge of the 45 car for the purpose. By virtue of this arrangement the car is centrally hinged in the dumping position. It may, however, be readily returned to its normal or upright position. As heretofore stated it is equally 50 adapted to be shifted to the dumping position in either direction, that is to say toward either edge of the car. Suitable mechanism is employed for imparting to the car body its initial lateral movement whereby it is 55 shifted sufficiently to cause it to automatically assume the dumping position.

Having briefly outlined my improved construction, I will proceed to describe the same in detail reference being made to the accompanying drawing, in which is illustrated an 60 embodiment thereof.

In this drawing, Figure 1 is a side elevation of a car equipped with my improvements. Fig. 2 is a sectional end elevation, the body of the car being shown in two positions, one 65 in full lines and the other in dotted lines. Fig. 3 is a top plan view of the car with the body part removed. Fig. 4 is an underneath view of the same illustrating the brake mechanism. Fig. 5 is a detail view of the 70 lever and ratchet mechanism for actuating the shaft carrying the central rollers for imparting the initial lateral movement to the dumping body. Fig. 6 is a central view of the 75 lower portion of the brake-operating lever. Fig. 7 is a detail view of one of the rollers, of smaller diameter mounted on the platform of the car.

The same reference characters indicate the 80 same parts in all the views.

Let the numeral 5 designate the car wheels; 6 the axles; and 7 the frame work of the car provided with a platform 8. Extending transversely across this platform are two end plates 9 and two intermediate plates 10. 85 These plates 9 and 10 are provided with central bearings 12 in which is journaled a longitudinally disposed shaft 13 carrying a number of axially aligned rollers 14. The shaft 13 protrudes from the platform of the 90 car at each end as shown at 15, each of these protruding extremities being efficient as shown at 16 to receive a crank 17 (not shown). As shown in the drawing the extremity 16 of the shaft is angular preferably 95 square in cross section whereby it is adapted to fit a crank socket of counterpart shape whereby it may be turned by the use of a crank if desired. This shaft, however, is more especially adapted for rotation by means of a 100 hand lever 17 having one extremity journaled on the shaft.

The shaft is provided adjacent the lever with a ratchet wheel 18 adapted to be engaged by a pawl 19 carried by the lever. 105 This pawl is reversible whereby it is adapted to actuate the ratchet wheel and shaft in either direction as circumstances may require. The platform is further provided adjacent its outer edges on both sides with a 110 number of rollers 20 and 21 of smaller diameter than the rollers 14. The body 22 of the

car, however, is provided at its outer edges with short blocks 23 which engage the rollers 20 and support the car body in a horizontal position, the said blocks compensating for the difference in diameter between the central rolls 14 and the rolls at the outer edges of the platform. This body part of the car is centrally provided with two pairs of angle plates 24 and 25, the said plates being secured to the bottom of the car in such a manner that they form keepers extending in opposite directions and open at their outer extremities to catch upon hinge pins 26 mounted at the extremities of the transverse plates 10 and in the path of the said keepers when the body of the car is shifted laterally in either direction. When shifted toward one edge of the car, the two keepers having their open extremities pointing in one direction, 15 catch upon the hinge pins, while when the body of the car is shifted in the opposite direction, the other two keepers catch upon the hinge pins. Hence when the angle irons or plates are connected with the keepers, the body of the car is hinged to assume the dumping position shown in full lines in Fig. 2. It is evident that the body of the car is in the position shown by dotted lines in Fig. 2, resting on the shaft 15 together with the 20 rollers 14 to be rotated, the friction of the said rollers will be sufficient to shift the car in the one direction or the other according to the rotation of the rollers, whereby it is given its initial lateral movement causing its 25 supporting blocks to leave the rollers 20, whereby it is caused to tilt and automatically assume the position shown in Fig. 2. The body of the car is provided with sides 27 hinged at 28 and normally locked in 30 the closed or upright position by spring catches 29.

My improved car is provided with suitable brake mechanism best illustrated in Fig. 4 in which the numeral 30 designates a lever centrally fulcrumed on the lower surface of the bottom of the platform as shown at 31, its opposite extremities being equipped with brake shoes 32. Near each extremity of this lever is connected a rod 33 to whose outer extremity is connected a lever 34 as shown at 35. This lever is fulcrumed as shown at 36, its arm above the fulcrum being provided with a socket 37 adapted to receive an operating handle 38. There is one of these levers 40 at each end of the car and the brakes may be applied from each end in a manner that will be readily understood.

From the foregoing description the use and operation of my improved push car will 45 be readily understood. Assuming that the body of the car is in the normal position as shown by full lines in Fig. 1 and by dotted lines in Fig. 2, if it is desired to cause the body to assume the dumping position, the 50 shaft 15 is rotated sufficiently to disengage

the supporting blocks 23 from the rollers 20, whereby the said body will slide automatically to the position shown in full lines in Fig. 2. This is the dumping position of the car, and it is also the position in which the 70 car may be loaded if desired. When the car is in this position it is easily returned to the platform, since it is centrally hinged whereby its opposite sides are equally balanced.

The end plates 9 are provided with upwardly projecting flanges 9^a which constitute retaining devices and also serve as guides for the body 22 of the car.

Having thus described my invention, what I claim is:

1. A car having a platform whose central portion and outer edges are provided with longitudinally alined rollers, the central rollers being of greater diameter than the edge rollers for the purpose set forth.

2. A car whose platform is provided with a number of centrally located longitudinally alined rollers, the opposite edges of the car being also provided with rollers of less diameter than the central rollers, and a body laterally movable on the platform, the central portion of the said body being adapted to rest upon the central rollers when the said body is in its normal position, the outer edges of the body being provided with blocks adapted to engage the rollers of lesser diameter, and suitable means for actuating the central rollers whereby an initial lateral movement is imparted to the car body, substantially as described.

3. In a car, the combination with a platform provided with rollers of different diameters, a body laterally movable on the rollers, the platform being provided with one hinge member and the body with another hinge member, the two members being normally separate and distinct from each other but located to be brought into operative relation when the body member is laterally shifted, substantially as described.

4. In a car of the class described, the combination with a platform, provided with a central roller, and an edge roller, a body resting upon the rollers and laterally movable, the edge roller being of less diameter than the central roller, and the body being provided with a block adapted to rest upon the roller of less diameter to compensate for the difference in size, the central roller being provided with a shaft, a lever loose on the shaft, and a ratchet and pawl connection between the lever and shaft whereby the central roller may be actuated to impart the initial lateral movement to the car body, substantially as described.

5. In a car of the class described, the combination with a platform, of a centrally located longitudinally disposed roller mounted upon a shaft, the edge roller being mounted at each edge of the car, a body mounted

on the rollers and laterally movable in both directions, the outer edges of the platform and the central portion of the body being provided with coöperating hinge members 5 normally distinct and separate from each other but adapted to be brought into operative relation when the car body is laterally shifted, substantially as described.

6. In a car, the combination with a plat-
10 form provided with rollers and upwardly projecting end flanges, and a body laterally

movable on the rollers between the said flanges which constitute retaining devices and form guides for the body during its lateral movement. -

15

In testimony whereof I affix my signature in presence of two witnesses.

GEORGE C. WORTMAN.
